(57) **CLAIM**

The ornamental design for an external corner strip, as shown and described.

DESCRIPTION

FIG. 1 is an upper right perspective view of an external corner strip embodying my new design;
FIG. 2 is a top view of the external corner strip of FIG. 1, the bottom being a mirror image thereof;
FIG. 3 is a left side view of the external corner strip of FIG. 1, the back being a mirror image thereof, and;
FIG. 4 is a front view of the external corner strip of FIG. 1, the right side being a mirror image thereof.
The drawings contain a symbolic break indicated in dot-dash broken lines. The portion between the break lines forms no part of the claimed design. The dash-dash broken lines illustrate portions of the external corner strip that form no part of the claimed design.
